STONE TRACER

Robert S. Mackenzie, North Chelmsford, Mass.,
assignor to H. E. Fletcher Company, Chelms-
ford, Mass., a corporation of Massachusetts

Application November 14, 1947, Serial No. 785,852

2 Claims. (Cl. 125—40)

1

This invention relates to a method and apparatus for cutting stone, and more particularly the invention is concerned with an improved stone tracing means for carrying out scoring or tracing operations, in order to break stone into desired shapes or sizes.

The task of scoring stone as commonly practiced requires a great deal of manual skill and is a slow and arduous operation. To this is added the danger of injury from stone particles or from the stone tracer flying out of the hand of the worker. All of these factors combine to impede stone cutting operations, as well as increasing the cost of making granite products.

The invention is in general directed to improving methods and apparatus for stone cutting, and to reducing the difficulties noted to the greatest extent possible. Specifically it is an object of the invention to facilitate manual tracing operations with improved tracing apparatus so that faster and more efficient cutting may be carried out.

I have found that improved results may be obtained by surrounding a stone tracer with a holder member which is arranged closely adjacent to the sides of the tracer in such a position as to substantially limit displacement of the tracer at the time it is struck with a hammer. An important feature of the invention, therefore, is a method and means for both mechanically limiting displacement of a stone tracer when hammered and positioning the tracer between blows of the hammer. A more correct alignment of the tool may thus be maintained, with less effort and faster operation. Other objects and novel features will appear from the following description of the invention.

In the accompanying drawings illustrating a preferred embodiment of the invention:

Fig. 1 is a perspective view showing the holder and stone tracer assembly of the invention;

Fig. 2 is a plan view of the holder and tracer;

Fig. 3 is a cross section taken on the line 3—3 of Fig. 2;

Fig. 4 is a cross section taken on the line 4—4 of Fig. 2;

Fig. 5 is a perspective view of a stone slab showing a line of scoring; and

Fig. 6 is a perspective view of a modification of holder member.

Considering the structure shown in the drawings in greater detail, 10 denotes a stone tracer which in general comprises a four-sided shank portion 12 and a relatively wider curved tracing edge 14. This tool is made of steel and is com-

2

monly held in position by hand and struck with a conventional stone hammer.

In accordance with the invention, I provide holder means for surrounding the tracer and loosely maintaining it in a substantially upright position, thus taking away a large part of the labor of holding the tracer by hand. The holder may be made of metal, wood, plastic or other desired material and includes a pair of parallel sides 16 and 18 which have flattened portions 20 and 22 extending laterally outward to provide flat bearing surfaces. These bearing surfaces may, if desired, be further provided with cushioning means 24 and 26, consisting of some resilient or yielding material such as layers of rubber or a rubber-like substance.

The sides 16 and 18 are preferably of a height less than the height of the stone tracer when the latter member at its lower extremity is supported in the same plane with the cushioning means 22 and 24, as may be readily seen from an inspection of Figs. 3 and 4. The upper part of the tracer 10, therefore, extends well beyond the holder and is free to be gripped and hammered when desired. I may also desire to provide the tops of the sides 16 and 18 with relatively wide flange portions 30 and 32. The flange portions are not essential to the holder but may provide a convenient supporting surface for the hand.

Numerals 34 and 36 refer to connecting partitions extending substantially at right angles between the sides 16 and 18 in spaced-apart relation. These partitions may be formed by molding the holder or by using separate pieces as of metal which are welded to the sides in the manner shown.

The connecting partitions serve two purposes: they constitute spacing means for maintaining the sides 16 and 18 spaced apart from one another a distance slightly greater than the thickness of the shank portion 12 of the tracing tool, measured in at least one dimension. At the same time, the two partitions are spaced apart from one another a distance also slightly greater than the thickness of the stone tracer, measured in a direction at right angles to the dimension just above referred to. By this arrangement, the shank portion 12 is surrounded on four sides with retaining walls or surfaces which are located sufficiently close to respective adjacent shank portions to prevent rotation of the tracing tool. Thus it will be seen that while some limited movement is provided for, there is a definite restriction on the amount of displacement of the tracing tool in a rotary direction and of course only limited movement

laterally or longitudinally is possible, and the tracer is loosely maintained in a substantial upright position.

The partitions 34 and 36 extend from a point beginning approximately at the top of the sides 16 and 18 downwardly to points somewhat above the relatively wider cutting edge 14 of the stone tracer as indicated in Fig. 4. It will be observed that the width of the cutting edge 14 substantially exceeds the width of the tool throughout the rest of its length. Therefore the tool can be inserted from the bottom of the holder upwardly into the position shown in Fig. 4 in which a slight clearance is provided for the tool to move vertically upward a short distance when hammered. It will be evident, therefore, that the tracer is limited in its movement in all directions except vertically downward, thus preventing any substantial displacement of the cutting edge 14 as it is being hammered and preventing stone chips from flying out at random.

In operation, the tracer is passed upwardly through the holder and the two elements are then located on a stone surface to be traced. The tool is then repeatedly hammered with the holder mechanically limiting displacement of the tool so that the operator may rapidly correct its position between each stroke. Concurrently with this operation, the operator moves the tracer and holder into successive cutting positions, with the tool in each position being located in a relatively central position within the holder, thus avoiding the need for carefully inspecting the placement of the cutting edge before each blow. In this way, a much faster and more accurate tracing line 38 may be formed on the stone surface, with a minimum of hazard and work.

An alternate form of the invention has been illustrated in Fig. 6 in which it will be observed that the two sides 16 and 18 are employed as be-

5

fore, but are joined together by end walls 40 and 42, extending between the side walls at their extremities. This arrangement provides for a lateral supporting of the tracing tool on two sides, thus preventing any tendency for the tool to turn or rotate, without necessarily limiting upward or vertical movement of the tracing tool when hammered.

I claim:

1. In combination a tool of the character described, presenting a cutting edge, a holder for maintaining the tool in a substantially upright position, said holder including a pair of parallel vertical sides which extend beyond the cutting edge to provide an elongated centering guideway, said sides being flanged laterally at their upper and lower edges, and a central shank support transversely mounted between the sides in a position to hold the cutting edge of the tool in substantially centered parallel relation to the vertical sides, said shank support terminating substantially above the bottom of the sides.

2. A claim corresponding to claim 1 in which the vertical sides are provided with resilient laterally extending cushioning elements attached at the under surfaces thereof.

ROBERT S. MACKENZIE.
